(57) **CLAIM**

The ornamental design for a vacuum gripper, as shown and described.

DESCRIPTIONFIG. 1 is a top-front perspective view of the vacuum gripper;
FIG. 2 is a top-rear perspective view thereof;
FIG. 3 is a bottom-front perspective view thereof;
FIG. 4 is a front view thereof;
FIG. 5 is a rear view thereof;
FIG. 6 is a top view thereof;
FIG. 7 is a bottom view thereof;
FIG. 8 is a left side view thereof; and,
FIG. 9 is a right side view thereof.

Light and shade expressed on the surface in each view are for specifying the shape of the surface. The broken lines are included for the purpose of illustrating environmental structure and form no part of the claimed design.

1 Claim, 9 Drawing Sheets(56)
